UNITED STATES PATENT OFFICE.

JOHN H. CHANDLER, OF INDIAN ORCHARD, MASSACHUSETTS.

PLUG-VALVE.

No. 904,307.

Specification of Letters Patent.

Patented Nov. 17, 1908.

Application filed November 11, 1907. Serial No. 401,618.

To all whom it may concern:

Be it known that I, JOHN H. CHANDLER, a citizen of the United States of America, residing at Indian Orchard, in the county of 5 Hampden and State of Massachusetts, have invented new and useful Improvements in Plug-Valves, of which the following is a specification.

This invention relates to improvements in 10 valves and more particularly to plug-valves, and in improved means for operating the plug element thereof for opening and closing the valve.

The invention herein described is broadly 15 applicable to either a straight-way valve or angle valve, both forms being shown to illustrate the applicability of my improvement.

My present invention is an improvement 20 over the construction shown and described in my prior Letters Patent of the United 25 States dated October 10, 1905, and numbered 801,648, and discloses a structure wherein certain defects which, in practice, are found to be objectionable to its satisfactory operation, are remedied.

In the drawings forming part of this application, Figure 1 is a vertical longitudinal sectional view through the operative parts of the valve and its casing on line 1—1 of 30 Fig. 2. Fig. 2 is a horizontal sectional view on line 2—2, Fig. 1, showing the position of the operative pin in the bottom part of the casing looking in the direction of the arrow. Fig. 3 is a detail perspective view of the 35 plug. Fig. 4 is a longitudinal vertical sectional view on the line 4—4 of Fig. 5, and Fig. 5 is a horizontal sectional view on line 5—5 of Fig. 4. Fig. 6 is a detailed perspective view of the plug as used in this form of 40 straight-way valve; while the plug shown in Fig. 3 is for an angle valve.

Referring to the drawings in detail, *a* designates a casing, *b* the bonnet, *c* the valve-stem that is provided with the usual packing-45 box or element *d* and collar *e* on the valve-stem. The lower end of the valve-stem is provided with a thread in the usual manner, as indicated at *f*.

The plug proper is indicated by the letter 50 *g* and is provided with communicating openings *h* and *i* forming an angle with each other, the opening *h* being arranged to register with the opening *j* in the casing, when the valve is open.

55 The bottom surface of the plug *g* is formed with a helical surface *k* equal in cir-

cumferential extent to ninety degrees. The extreme ends of this helical surface *k* are provided with shoulders *m* and *n*.

Adjustably arranged in the bottom of the 60 casing *a*, and offset from the center line of the casing is a pin *o* that is arranged to engage the surface *k*.

It will be noticed that the lower end of 65 the plug *g* is milled back from its outer surface so as to form a web portion *q*, and also a web *q'* on the part of the plug towards the center thereof.

The operation of the valve is as follows: Referring to Fig. 1 (which shows the valve- 70 plug in its closed or seated position), the operator rotates the valve-stem by means of the usual hand-wheel in a left-handed movement which causes the left-handed thread *f* to elevate the plug *g* from its seat in the 75 casing and draw the same firmly against the portion *r* of the stem until the friction between the plug and stem is great enough to rotate the plug and bring the opening *h* in the plug into register with the opening *j* of 80 the casing. The shoulder portion *n* at one extremity of the helical surface *k* will then strike the threaded stem *o* and limit the rotary movement of the plug to 90 degrees. In order to close the valve, the operator ro- 85 tates the hand-wheel right-handedly causing the plug *g* to descend, and as it de- scends it is forced against the pin *o*. The helical surface *k* on the lower part of the plug will cause the same to be rotated upon 90 the continued rotation of the stem until the pin *o* is brought against the other shoulder *m* of the plug; at the same time the plug will be firmly seated in the casing *a*, and the opening *j* in the casing *a* closed. 95

One advantage in making the pin *o* adjustable is that it readily permits its removal and allows the plug *g* to be accurately ground into the casing *a*, and after this grinding is finished, the pin *o* is inserted the 100 proper distance and firmly locked by means of the set-nut *s*.

Referring to Figs. 4, 5, and 6, which show a straight-way valve: The lower end portion of the plug *t* is milled so as to form the 105 groove *u* and at the same time leave a web *v*. The bottom portion of this groove is the same in shape and extent as that already described in connection with the plug *g* and shown in Figs. 1, 2, and 3 of the drawing, 110 and is provided with the limiting stops *w* and *x* for properly alining the opening *y* in

the plug with the openings z and 2 in the opposite sides of the casing 3 .

The operation of the plug t in opening and closing this valve is the same as that described in connection with Figs. 1, 2 and 3. The pin 4 is also made adjustable and secured in place by means of the lock-nut 5 so as to permit the plug being accurately ground to its seat in the casing.

10 In both of the forms herein described, the use of the removable pins not only cheapens the construction over that shown and described in my prior patent above referred to, wherein ribs are employed for causing 15 the rotation of the valve-plug, but it also results in greater accuracy and adjustment of the parts, since it is found to be a difficult matter to make a good fit between the ribs and the lower end of the plug. Furthermore, this construction permits an angle-valve to be made; but in my prior patent the ribs would not permit the construction of such a kind of valve. The pins o and 4 also serve the purpose of properly maintaining 25 the vertical movements of the plug during the rising and falling movements of the same.

What I claim, is:—

1. As an improvement in valves, a casing, 30 a plug, the lower end of which is provided with a helical surface, limiting means projecting into the casing and engaging said surface, the plug being formed with limiting stops at the extremities of said surface, 35 whereby rotary movement is imparted to the plug and the extent of rotation is limited, and means for imparting a vertical movement to the plug.

2. A valve having in combination a casing, 40 a conical shaped plug, the lower portion of which is provided with a groove having a helical surface, a web element between the helical surface and the outer surface of the plug, the groove having abutments at its ex-

treme ends, and means mounted on the casing 45 and projecting into the groove, engaging the helical surface, whereby when a vertical movement is imparted to the plug the same will be rotated by the engagement of the projecting means, and the limit of rotation 50 will be determined by the abutments.

3. A plug valve having in combination with the casing thereof, an adjustable member secured to the casing and projecting into the interior thereof and parallel with the 55 axis of the plug, the plug being provided with a helical surface for engaging the adjustable member whereby when a vertical movement is given to the plug the same will be rotated.

4. A valve having in combination a plug, the lower portion of which is formed with a groove having a helical surface and limiting stops at its end portion, an adjustable pin 60 mounted in the casing and engaging the 65 helical surface of the groove, whereby the plug may be ground to its seat before assembling.

5. A valve having in combination, a casing, a tapered plug, the lower end of which 70 is provided with a helical surface, a pin mounted in the casing and engaging said surface, means for operating the plug comprising a valve-stem, threads thereon for engaging threads in the plug, a shouldered 75 portion on the stem, whereby when the stem is operated in one direction the plug is unseated and brought against the shouldered portion permitting the plug and stem to rotate together to open the valve, as described, and whereby when the stem is rotated in the opposite direction rotary movement is imparted to the plug to close the same.

JOHN H. CHANDLER.
